UNITED STATES PATENT OFFICE.

ARON ECKMANN, OF BERN-WABERN, SWITZERLAND, ASSIGNOR TO SCHWEIZ. SERUM-
& IMPFINSTITUT BERN, OF BERN, SWITZERLAND, A SWISS CORPORATION.

PROCESS OF CONVERTING MEDICAMENTS, ANTISEPTIC AGENTS AND CAUTERIZATION
MEANS INTO A STABLE AND READILY DOSABLE FORM.

No Drawing. Application filed May 27, 1924, Serial No. 716,277, and in France April 28, 1924.

My invention has for its object to convert therapeutically valuable substances, particularly those which are difficultly soluble or insoluble and are used as medicaments, 5 antiseptic agents or cauterization means, into a stable and readily dosable form, without the said substances suffering a chemical change.

As is well known it is not easy, but even 10 frequently impossible, correctly to dose certain antiseptic agents and cauterization means used in dentistry for killing the nerves of teeth. A particularly important practical case is the use of arsenic trioxide as a 15 cauterization agent. Heretofore the dentist has had to put a wad of cotton wool into the arsenic trioxide and then insert the wad into the tooth irrespective of whether too much or too little adhered to the wad. 20 When the correct dose was exceeded, undesirable or even dangerous results, for example necrosis, were very frequently the consequence. These drawbacks which, as mentioned above, occur also with antiseptic 25 agents and other medicaments, particularly those consisting of difficultly soluble or insoluble substances, are obviated by the present invention.

The process forming the subject-matter of 30 the present invention comprises the steps of uniformly distributing the medicaments, antiseptic agents and cauterization means, irrespective of their solubility, in jellies of any suitable kind, and then drying the jelly.

It is well known that jellies, which are 35 semi-solid systems of a colloidal nature, behave almost like pure aqueous solutions as regards chemical compounds capable of diffusion, that is to say, under given conditions the chemical compounds enveloped in the jelly act by diffusion.

Example.

10 grammes of arsenic trioxide are put 40 into 150 ccm. water, are heated and filtered. The filtrate is slowly mixed with a solution containing a high percentage of gelatine, and then this mixture is evaporated on the 45 water bath to one third of its volume. When cold the mass forms a jelly which is dried 50 to constant weight at a temperature of about 15°-18° C. The amount of arsenic trioxide is quantitatively determined in this mass. The dry solid mass is then molded into any

desired shapes, such as tablets, cubes, prisms, 55 balls and so on, whereof each contains an exactly determined dose of arsenic trioxide.

In an exactly analogous manner, the so-called cobalt filling, which is also used in dentistry for cauterizing purposes, can be 60 made. A weighed quantity of bits of cobalt is intimately mixed with a highly concentrated gelatine solution, this being facilitated by adding some heated water, and the mixture is heated on the water bath and 65 allowed to congeal. After having been completely dried in vacuo, a homogeneous mass is obtained which can be dosed after being weighed.

One may also practice the process by suspending, as described above, two different substances capable of chemically reacting one on the other, independently of each other in a highly concentrated gelatine solution, and then mixing together the still liquid or 70 semi-liquid masses and drying the mixture. Thus, for example, one can mix the above described jelly containing arsenic trioxide with a jelly containing an oxide, hydroxide e. g. magnesium oxide, ferric hydroxide, or 75 salt of the alkaline-earth, or precious, or heavy metals, which acts as an antidote of the arsenic trioxide. If two such jellies are placed on the pulp of a tooth with the jelly containing the arsenic trioxide at the bottom, the arsenic trioxide will first diffuse 80 through the jelly and act on the pulp. Any excess of arsenic trioxide is made harmless by the subsequent diffusion of the antidote referred to. 85

In each case one may use as jelly any 90 convenient and suitable substance, such as, for example, gelatine, agaragar, cellulose and the like.

The above mentioned examples relate 95 solely to cauterization agents. It is, however, to be distinctly understood that the process can be employed just as well with substances serving as antiseptic means and medicaments.

I claim:

1. The process of producing a means for killing the nerve of a tooth, which comprises mixing suitable substances irrespective of their solubility in a well-known manner with 105 a suitable jelly, uniformly distributing the substances therein, then drying the jelly, and then molding it into tablets or the like so

that each tablet contains a predetermined, definite, and known quantity of the active substance.

2. The process of producing means for killing the nerve of a tooth, which comprises suspending two or more different substances capable of mutual reaction, one being a cauterizing agent and the other an antidote of the same, independently of each other in

suitable jellies and uniformly distributing ¹⁰ said substances in said jellies, then combining the jellies with each other, drying the same and finally molding the combined substances into tablets or the like, so that each tablet contains a predetermined, definite and ¹⁵ known quantity of the active substances.

ARON ECKMANN.
